UNITED STATES PATENT OFFICE.

J. PEATFIELD, OF IPSWICH, MASSACHUSETTS.

MANUFACTURING KNIT GLOVES.

Specification of Letters Patent No. 20,893, dated July 13, 1858.

To all whom it may concern:

Be it known that I, JAMES PEATFIELD, of Ipswich, in the county of Essex and State of Massachusetts, have invented a new and 5 useful Improvement in the Manufacture of Knitted Gloves; and I do hereby declare that the following is a full, clear, and exact description of the same, reference being had to the accompanying drawing, making part 10 of this specification, in which—

Figure 1, is a front view of a glove illustrating my improvement. Fig. 2, is a transverse section of the same at the junction of the fingers with the hand.

15 Similar letters of reference denote like parts in both figures.

The object of this invention is to produce seamless knitted gloves by machinery. The invention consists in knitting the hand of a 20 glove and the fingers and thumb thereof separately, each in circular form and consequently without seam and uniting them by knitting them together in the manner hereinafter described.

25 The hand and the fingers and thumb having been knitted separately in circular machines with a sufficient number of loops dropped in one of the courses of the hand to make an opening to receive the thumb; 30 the marginal course of loops at the bottom of the fingers is united with the marginal course at the top of the hand by taking the

end of the thread of each finger and with a common sewing-needle or needle of other form taking it through the loops of the 35 marginal course of the hand and through those of the marginal course of the finger in a manner to form a uniting course of loops as represented in Fig. 1, where the marginal courses of loops of the hand and 40 one finger are represented in black color, and the uniting course in red. The fingers are also united with each other in a similar manner by taking the thread of each through the marginal loops of the next one on either 45 side of it at the parts *a*, *a*, Fig. 2, which require to be united. The lower marginal course of loops of the thumb is attached to the marginal loops of the opening prepared for it, in a similar manner. 50

I do not claim to be the inventor of a seamless knitted glove, as such are knitted by hand. But—

What I claim as my invention, and desire to secure by Letters Patent, is:— 55

The manufacture of seamless knitted gloves by knitting the hand and the fingers and thumb separately, and uniting them in the manner substantially as described.

JAMES PEATFIELD.
